ABSTRACT: A stethoscope is provided having ear tubes connected by a resilient band which permits swinging movement of the free ends of the ear tubes toward and away from each other in a plane for insertion for use and removal but resists displacement of the ear tubes from that plane, the ends of the resilient band having struck out projections engaged in slots in the tubes and having wings extending partially around the ear tubes, the ends of the resilient band being held in engagement with the ear tubes by external tubular synthetic plastic collars.

STETHOSCOPE

BACKGROUND OF THE INVENTION

1. Field of the Invention

This invention relates to stethoscopes and more particularly to a stethoscope having an improved resilient connection between the ear tubes.

2. Description of the Prior Art

Various connections have heretofore been proposed between the ear tubes of stethoscopes.

A common form of connection comprises a resilient metallic band with sleeves at each end which surround the tubes and are in frictional engagement therewith. The rigorous use to which stethoscopes are subjected results in loosening of the sleeves.

The spring material from which such connections are formed makes it difficult and costly to secure such a band to tubes of different material and which advantageously are of brass or aluminum.

The stethoscope of the present invention has the connector secured to the ear tubes in a simple but effective manner which does not require soldering or the like.

SUMMARY OF THE INVENTION

In accordance with the invention, a stethoscope is provided having the metal ear tubes connected by a resilient connecting band which permits swinging movement of the free ends of the ear tubes toward and away from each other in a plane for insertion for use and for removal but which resists displacement of the ear tubes from that plane, the ends of the band having end struck out projections engaged in slots in the ear tubes, and having partial side gripping wings, the end portions of the resilient band being held in engagement with the ear tubes by external collars, preferably of tubular synthetic plastic material.

It is the principal object of the invention to provide a stethoscope having a simple but effective resilient connection between the ear tubes which permits easy adjustment of the ends of the ear tubes toward and away from each other in a plane for use and for removal but prevents displacement of the ear tubes as by turning of the same out of that plane.

It is a further object of the invention to provide a stethoscope having an improved connection between the ear tubes and which will have a long useful life.

Other objects and advantageous features of the invention will be apparent from the description and claims.

BRIEF DESCRIPTION OF THE DRAWINGS

The nature and characteristic features of the invention will be more readily understood from the following description taken in connection with the accompanying drawings forming part thereof, in which:

FIG. 1 is a view in elevation of a stethoscope in accordance with the invention;

FIG. 2 is a transverse sectional view, enlarged, taken approximately on the line 2—2 of FIG. 1;

FIG. 3 is a fragmentary longitudinal view partly in elevation and partly in section on the line 3—3 of FIG. 2;

FIG. 4 is a transverse sectional view, taken approximately on the line 4—4 of FIG. 3; and

FIG. 5 is a partial exploded perspective view of the end connection with the tubular sleeve omitted.

It should, of course, be understood that the description and drawings herein are illustrative merely and that various modifications and changes can be made in the structure disclosed without departing from the spirit of the invention.

5 Like numerals refer to like parts throughout the several views.

DESCRIPTION OF THE PREFERRED EMBODIMENT

Referring now more particularly to the drawings, a 10 stethoscope is shown at 10 having ear tubes 11 preferably of metal, such as stainless steel, brass or aluminum, with rubber or plastic ear tips 12 thereon. The ear tubes 11 have flexible tubes 13 of rubber or synthetic plastic extending therefrom to a chestpiece 14 of any desired type.

15 A binaural spring 15 is provided preferably of spring steel and of special configuration as hereinafter described.

The spring 15 has a central band portion 16, which is preferably wider at the center than at the ends, and is of U-shape.

20 The spring 15 has end portions 17 with arcuate terminal wings 18 which extend partially around the tubes 11. The end portions 17, between the wings 18, have struck out projections 19 which engage in slots 20 in the tubes 11.

In surrounding relation to the tubes 11 at the locations 25 thereof where the projections 19 engage in the slots 20 and the wings 18 extend partially around the tubes 11, holding collars 21 are provided preferably of synthetic plastic material and preferably shrunk in place so as to tightly grip the wings 18 and the tubes 11.

The collars 21 hold the end portions 17 of the springs 15 firmly in place, permit swinging movement of the ear tips 12, of the ear tubes 11 toward and away from each other in a plane. Movement as by turning of the ear tips 12, out of this plane is resisted by the shape of the central portion 16 of the spring 15 and by the rigid holding of the end portions 17 by the collars 21.

We claim:

1. In a stethoscope having rigid ear tubes with terminal ends on which flexible tubes are engaged and a chestpiece connected to said flexible tubes, the improvement which comprises

a binaural spring having end portions engaging said ear tubes above said terminal ends, interengaging portions on each of said ear tubes and said spring end portions for preventing relative rotation and longitudinal axial movement of said ear tubes and said spring end portions but permitting relative movement of the free ends of the ear tubes in a plane, and

a collar in surrounding gripping relation to said spring end portions and said ear tubes spaced from said terminal ends and holding said interengaging portions in engagement.

2. A stethoscope as defined in claim 1 in which said interengaging portions comprise a slot in each of said tubes and a projection on said spring end portions disposed in said slots.

3. A stethoscope as defined in claim 1 in which said binaural spring is U-shape and of strip material and is wider at the midportion thereof.

4. A stethoscope as defined in claim 1 in which said collar is of synthetic plastic material and has a shrunk fit.
